UNITED STATES PATENT OFFICE

2,252,380

TELEGRAPH SIGNAL REGENERATOR

Alfred Kahn, Hollis, N. Y., assignor to Radio Corporation of America, a corporation of Delaware

Application February 29, 1940, Serial No. 321,398

8 Claims. (Cl. 178—69.5)

This invention relates to a telegraph signal regenerator and more particularly to an electronic system for regenerating synchronous signals which may have been deformed in traveling through the conducting medium from the transmitter to the receiver.

It is an object of my invention to provide a regenerator which is simple in construction, easy to maintain, and which requires a minimum number of parts.

It is a more specific object of my invention to provide a regenerator which eliminates, insofar as possible, mechanical commutation means, and which provides dependable regeneration of the received telegraph signals.

It is a still further object of my invention to provide a regenerator which depends for its operation upon properly timed locally generated impulses, these impulses being coordinated with the received signals for controlling a so-called locking circuit of conventional type.

In carrying out my invention I provide means dependent upon the normal rate of reception of the signalling elements for controlling a multivibrator. The output frequency of this multivibrator is held in synchronism by means well known in the art. Such means may, for example, be of the type shown and described in an application Serial No. 169,365, filed October 16, 1937, by Richard E. Mathes, and assigned to the assignee of the instant application. Mathes showed a synchronous corrector applicable to a receiving distributor for a multiplex system. Such a corrector may be employed for maintaining the frequency and phase of my multivibrator suitably coordinated with the mean frequency of reception of marking signal peaks. However, other means of control of the multivibrator frequency may be adopted, whether mechanical or electromechanical in structure, provided a source of substantially constant frequency impulses is made available. This multivibrator is employed in combination with rectified pulses representing marking elements of the telegraph signals so as to regenerate signals of substantially square-wave formation, as is done when a conventional locking circuit is properly controlled. An important feature of my invention, therefore consists in the provision of a circuit arrangement whereby the incoming signals and the oscillator are caused to cooperate to control the locking circuit.

My invention will now be described in more detail, reference being made to the accompanying drawings in which

Figure 1 shows diagrammatically a preferred circuit arrangement for carrying out the invention;

Fig. 2 shows a typical wave shape representing the unfiltered output from a rectifier which in turn is controlled by a multivibrator;

Fig. 3 shows the wave shape of output energy from an amplifier stage following the rectifier whose output is as shown in Fig. 2;

10 Figs. 4a, 4b, 4c and 4d show respectively different time graphs of signals and voltages appearing across different portions of the circuit arrangement;

Fig. 5 shows a detail of means for utilizing a 15 multivibrator whose frequency is equal to twice that of the signal frequency; and,

Figs. 6 and 7 show time graphs of resultant impulses obtained by the use of the means shown in Fig. 5.

Referring first to Fig. 1, I show a multivibrator MV having an input circuit connected thereto which synchronizes its operation in dependence upon a phase corrector unit PC, the latter being operative in dependence upon the arrival moments of the signals. The output from the multivibrator is substantially sine wave in formation and is fed across a transformer 1 to the input circuit of an amplifier tube 2. The output from this amplifier is fed across a transformer 3 to a circuit which includes a full wave rectifier 4 and a load resistor 27. The cathode of the rectifier 4 is grounded and its anodes are connected to the terminals of the secondary on the transformer 3. This secondary has a mid-tap connected to one terminal of resistor 27, the other terminal of which is connected to the grounded cathode.

An electron discharge tube 5 has a control grid connected to the mid-tap on the secondary of transformer 3. This tube is, therefore, controlled by the rectified voltage developed across resistor 27. The output from the tube 5 is utilized in a half wave rectifier tube 6 having in shunt therewith a resistor 7 of high ohmic value.

45 The unfiltered output from the rectifier 4 produces a wave shape as shown in Fig. 2. The tube 5 is held at cut-off by the average negative bias produced by the rectifier 4 and passes current only when the sharp bias peaks approach zero. The anode voltage excursions of the tube 5 are shown in Fig. 3.

50 The purpose of the resistor 7 is to permit a slow charge to be accumulated on the capacitor 8 during moments of peak voltage of the anode in tube 5. The tube 6, being conductive in one

direction only, functions when tube 5 becomes conductive to permit the condenser 8 to discharge rapidly.

The locking circuit is shown within a rectangular broken line enclosure and comprises discharge tubes 26 and 21 in combination with a number of resistive circuits interconnecting the electrodes and the power supply source. The output leads from the locking circuit are designated OL and may be considered as feeding to a recorder unit or to keying means for retransmitting the received signals.

The locking circuit as herein shown was disclosed in U. S. Patent No. 1,844,950, granted February 16, 1932, to J. L. Finch. Reference is made to that patent for a more detailed explanation of the operation thereof.

When tubes 5 and 6 become conductive and condenser 8 discharges, it will be seen that the grid of tube 26 becomes biased to cut-off and raises its anode to maximum voltage. This causes the bias on the grid of tube 21 to approach zero, whereupon the tube 21 becomes conductive for a period representing a marking signal element and is held in this stable state until condenser 19 discharges impulsively. The application of such an impulse will now be explained.

From the radio receiver impulses are applied across the amplifier 9 to a transformer 16 and thence to the grid of an amplifier tube 11. The output from the tube 11 is fed across the primary of a transformer 12 whose secondary has terminals connecting respectively with the anodes of a full wave rectifier 18. This secondary is also provided with a mid-tap connecting with one terminal of a load resistor 16 and with the control grid in an amplifier tube 15. The cathode of the rectifier 18 is connected to a junction lead between resistors 16 and 27 so as to effectively place the circuits of rectifiers 4 and 18 in series.

A keyed tone signal is supplied to transformers 10 and 12 and appears as a rectified signal voltage across resistor 16. This resistor is shunted by a condenser 14 so as to smooth out the ripple component appearing in the rectified signal. A suitable bias voltage is thereby obtained for controlling the grid of amplifier tube 15.

The output from tube 15 is utilized in the same manner as the output from tube 5, but for the purpose of operating the locking circuit in the reverse direction. This is accomplished by means of a half wave rectifier tube 18 in shunt with which is disposed a resistor 17 of high ohmic value. The anode of the rectifier 18 is connected to one side of the condenser 19, the other side of which is connected to the grid of tube 21 in the locking circuit.

On reception of the marking signal peaks, the rectified voltage across resistor 16 is a maximum and biases the tube 15 to cut-off. The voltage on the cathode of rectifier 18 floats between ground potential and the negative potential derived from the rectifier 4, the latter being prevalent most of the time and the former during the brief intervals of current interruption across resistor 27. During these brief intervals the grid bias in tube 15 becomes slightly less negative than at other times, but not sufficiently so for effecting any control of tube 21 in the locking unit.

On reception of a spacing signal simultaneously with the arrival of a zero-voltage peak at the top end of resistor 27, tube 15 draws sufficient current to enable condenser 19 to discharge substantially fully. This action results in blocking tube 21 at the negative wave crest of a spacing

signal. In case the spacing signal is prolonged beyond the next instant of zero voltage drop across resistor 27, the action of condenser 19 will predominate over that of condenser 8, so

that tube 21 will remain blocked until the arrival of succeeding marking signal. Thus, as shown in Fig. 4b, the anode voltage of tube 15 dips slightly as at 30, and only once at the crest of a short marking signal m_1 (Fig. 4a), but dips repeatedly as at 31 during a prolonged marking signal m_2 . Here the periodic dips 32 of anode voltage in tube 5 (Fig. 4c) are permitted to maintain control. Furthermore, during short space intervals S_1 and long space intervals S_2 the anode voltage of tube 15 dips to its lowest value and blocking control of tube 21 is likewise maintained. The locking circuit will, therefore, be tripped by the simultaneous occurrence of a spacing signal peak and an impulse from the multivibrator MV. The action of the rectifier 16 and shunt resistor 17 is identical with that of rectifier 6 and shunt resistor 7, except that they follow the control of the spacing signals, whereas the periodicity of the latter is constant.

It will be seen from the above description that the tube 15 is either unblocked slightly by impulses from the rectifier 4 as when marking signals occur, or is unblocked fully in the presence of spacing signals plus an impulse from the rectifier 4, in which case the rectified current across the tube 16 is of sufficient amplitude to fully discharge the condenser 19 and thereby to bias the tube 21 to cut-off. This simultaneous application of pulses from rectifiers 4 and 18 is in excess of the discharge effect across rectifier 6 alone and, therefore, the tube 21 is controlled predominantly over the control of tube 26. In other words, the effect of the impulses from the multivibrator is switched to control tube 26 for biasing the same to cut-off upon reception of a marking signal and is switched to control tube 21 upon reception of a spacing signal. The time of occurrence of the pulses is held to the center of each baud by means of the correction unit PC so as to pass the signal to the locking circuit during its best portion.

A typical time graph of a received signal representing dots and dashes and somewhat distorted from the original square-wave form is shown in Fig. 4a. Figs. 4b, 4c and 4d are time graphs drawn to the same time scale as Fig. 4a.

In Fig. 4b the anode voltage of tube 15 is shown. The deep depressions occur during spacing intervals and represent times when tubes 15 and 18 are conductive. Tube 15 is only slightly un-blocked at peaks of the marking signal.

Fig. 4c shows voltage changes on the anode of tube 5 which result from the operation of the multivibrator MV. The voltage is high for the greater part of the time because the rectifier 4 biases tube 5 substantially to cut-off. Momentarily, however, the output from rectifier 4 is substantially reduced to zero and the bias on the grid of tube 5 rises to substantially zero, thus permitting the condenser 8 to discharge quickly across rectifier 6 and the space path of the tube 5. It is during these discharge intervals of condenser 8 that tube 26 in the locking circuit is biased to cut-off.

Fig. 4d shows the regenerated signal having a square-wave formation. This is the signal which is delivered by the locking circuit at the output terminals OL.

Referring now to Fig. 5, I show a detail of an arrangement wherein the control frequency from

the multivibrator MV may be utilized even though it possesses twice the frequency of the signal frequency. Such an arrangement has certain practical advantages which will be obvious to those skilled in the art. To meet the conditions stated a quarter-phase rectifier is employed. The transformer 3 is the same as shown in Fig. 1. The rectifier 4 is also the same as shown in Fig. 1, but is supplemented by a half-wave rectifier 24. The phase of the voltage delivered to rectifier 24 is in a quadrature relation to the phase of the voltages delivered to the full-wave rectifier 4. This is brought about by the use of a conventional system of capacitor C and resistor R in series with one another, the interconnection between them being also connected to the anode of the rectifier 24. The cathodes of the rectifiers 4 and 24 are interconnected and lead to the grounded end of resistor 27. The other end of resistor 27 is connected with the mid-tap on the secondary of transformer 3, the same as shown in Fig. 1.

By means of the arrangement shown in Fig. 5 certain voltages are delivered across resistor 27 as shown in Fig. 6. The combined rectifier voltage, however, is shown in Fig. 7. It will be noted that the sharp peaks of no voltage appear only at every other cycle of the multivibrator frequency, intervening voltage dips being counteracted by the output from the half-wave rectifier 24. It is only the negative peaks which represent substantially no voltage across resistor 27 which are effective in controlling the tube 5.

It will be understood by those skilled in the art that the phase corrector which is interposed between the radio receiver and the multivibrator need not necessarily include mechanically rotatable elements, since it is possible to provide synchronous control of the multivibrator MV by means of a local oscillator whose frequency is subject to phase correction. A phase corrector of that type has been disclosed by E. R. Shenk in his application Serial No. 326,902, filed March 30, 1940.

It will also be understood by those skilled in the art that various modifications of the invention may be adopted without departing from the spirit and scope of the invention as defined by the claims to follow.

I claim:

1. In a telegraph signal regenerator, a locking circuit for keying the marking impulses of a signal train, a multivibrator capable of generating self-sustained oscillations subject to phase correction by a train of received signals, means responsive to the operation of said multivibrator for timing the shifts of said locking circuit from one to another state of electrical stability, means operative during reception of the wave peak of a marking signal of baud unit length for producing one of said shifts in one sense, means operative during the reception of a wave valley representing a spacing signal of baud unit length for producing one of said shifts in the opposite sense, and means inherent in the cooperative action of the aforesaid means for continuing the state of electrical stability to which said locking circuit is shifted during the prolongation of marking and spacing signals beyond an interval of baud unit length.

2. In a telegraph signal regenerator, a locking circuit for keying the marking impulses of a signal train, an oscillation generator having a substantially sine-wave output at a frequency closely approximating the baud unit periodicity

of a train of received signals, means for continuously correcting the phase of said generator with respect to the marking wave peaks of said signals, a full-wave rectifier receptive of energy from said generator, a second full-wave rectifier receptive of tone frequency currents representing marking signals, two series-connected load resistors, each appropriately disposed in circuit with a respective one of said rectifiers, and means comprising two capacitive circuits for producing shifts in opposite senses of electrical stability of said locking circuit, each of said capacitive circuits including means for slowly storing a charge when an associated one of said load resistors draws current, and for suddenly dissipating said charge when that resistor ceases to draw current.

3. The combination, according to claim 2, in which the stated means in each of said capacitive circuits is constituted by a half wave rectifier shunted by a resistor.

4. The method of controlling a locking circuit for the purpose of regenerating telegraph signals received at a substantially fixed baud frequency, which comprises generating a sine wave, continuously correcting the phase of said wave in accordance with said received signals, separately rectifying the energies of said wave and of the marking elements of said signals, slowly accumulating a capacitive charge during each moment of rectification of the sine wave energy, slowly accumulating another capacitive charge during reception of each marking signal element, periodically and suddenly dissipating the first mentioned charge at said baud frequency, suddenly dissipating the second mentioned charge simultaneously with the first whenever the reception of a spacing signal is coincident, causing said locking circuit to shift from a first to a second state of electrical stability in response to the dissipation of the first mentioned charge only, and causing said locking circuit to shift in an opposite sense in response to the simultaneous dissipation of both said charges.

45. 5. A telegraph signal regenerator comprising a locking circuit having two discharge tubes, the electrodes of which are resistively interconnected in such manner that one is normally blocked while the other draws current and the blocking of each tube by an extraneous negative impulse causes the other tube to become conductive, each tube having a blocking bias circuit connected between its cathode and control grid, each said control grid being coupled through an appropriate storage capacitor to a suitable control circuit, a source of periodic impulses delivered at a baud-frequency rate corresponding to the speed of reception of a train of telegraph signals, a full-wave rectifier responsive to said impulses, a second full-wave rectifier responsive to received tone frequency energy representing marking elements of said signals, two inverter tubes, each under the respective control of one of said rectifiers, and means in each of said control circuits for effecting a slow charge and a rapid discharge of its appropriate storage capacitor in response to the blocking and unblocking respectively of an appropriate one of said inverter tubes, said rectifiers being operative to initiate an effective discharge from one only of said capacitors during reception of a marking signal and to cause the second capacitor to discharge more effectively than the first during reception of a spacing signal.

70. 6. In a telegraph signal regenerator a locking

circuit for re-shaping the marking impulses of a signal train, said marking impulses being of normal length equal to a "baud" and multiples thereof, and being separated by spacing intervals normally of baud-length and multiples thereof, means including a self-sustaining oscillator having a normal frequency equal to a multiple of the baud frequency for timing the shifts of said locking circuit from one to another state of electrical stability, means responsive to the reception of signals to be re-shaped for correcting the phase of said oscillator, means under control of said oscillator for producing short sharp impulses of baud-frequency, and means under the joint control of the received signals and of the last said means for fixing the moments when the electrical stability of said locking circuit is shifted.

7. In a telegraph signal regenerator a locking circuit for re-shaping the marking impulses of a signal train, said marking impulses being of normal length equal to a "baud" and multiples thereof, and being separated by spacing intervals normally of baud-length and multiples thereof, means including a self-sustaining oscillator having a normal frequency equal to the baud frequency for timing the shifts of said locking circuit from one to another state of electrical stability, means responsive to the reception of sig-

nals to be re-shaped for correcting the phase of said oscillator, means under control of said oscillator for producing short sharp impulses of baud-frequency, and means under the joint control of the received signals and of the last said means for fixing the moments when the electrical stability of said locking circuit is shifted.

8. In a telegraph signal regenerator, a locking circuit for keying the marking impulses of a signal train, an oscillator capable of generating self-sustained oscillations subject to phase correction by a train of received signals, means responsive to the operation of said oscillator for timing the shifts of said locking circuit from one to another state of electrical stability, means operative during reception of the wave peak of a marking signal of baud unit length for producing one of said shifts in one sense, means operative during the reception of a wave valley representing a spacing signal of baud unit length for producing one of said shifts in the opposite sense, and means inherent in the cooperative action of the aforesaid means for continuing the state of electrical stability to which said locking circuit is shifted during the prolongation of marking and spacing signals beyond an interval of baud unit length.

ALFRED KAHN.
